Inventor:
Henry Gount.

United States Patent Office.

HENRY YOUNT, OF DAYTON, OHIO.

Letters Patent No. 67,699, dated August 13, 1867.

IMPROVEMENT IN HARNESS-MOTION FOR LOOMS.

The Schedule referred to in these Letters Patent and making part of the same.

TO ALL WHOM IT MAY CONCERN:

Be it known that I, HENRY YOUNT, of Dayton, in the county of Montgomery, in the State of Ohio, have invented a new and improved Mode of Constructing Looms; and I do hereby declare that the following is a full and exact description thereof, reference being had to the accompanying drawings, and to the letters of reference marked thereon.

The nature of my invention consists in providing lateral guides for the harness-frames, and the manner of giving motion to the same.

To enable others skilled in the art to make and use my invention, I will proceed to describe its construction and operation.

The figure represents a side view of a loom containing my improvements.

A represents a quadrangular frame, the dotted lines at H and P showing the position of the cross-pieces. To the cross-pieces H H are attached the guides F F, which have a series of grooves in which the harness-frames B move. To each of the frames is attached an arm, C, and to each arm C is pivoted an arm, D. The lower end of the arm C is provided with a curved slot, p, and through this slot and into arm D passes a set-screw to retain the two arms together. The arms D are connected to the levers K K by a pin, and these levers have a series of holes by which the movements of the harness-frames may be increased or diminished, and the screw in the curved slot p holds the arms C D rigidly together after the pin on the arm D is in the desired hole in the lever K. To the cross-piece P are attached posts E, through which a pin passes, forming a fulcrum for the levers K. On the opposite side of this cross-piece are attached the guides I, and likewise the supporting-pieces O, which bear the shaft to which the cams G are attached. An exact description of the cams is unnecessary, as they are identical with those in common use, and give to the levers an alternating movement, which are likewise similar to those in use. The crank r is attached to the shaft to show the movement. In a practical machine the cam-shaft is connected to the main shaft of the loom by a bevel-gear.

I have shown but two cams, levers, and harness-frames, but I do not desire to limit myself to any particular number of cams, &c.

Operation: On turning the cams the levers are made to oscillate, thus communicating to the harness-frames the requisite motion for weaving.

Having described my invention, what I desire to secure by Letters Patent, is—

The combination of the arms C and D, levers K, cams G, and frame A, constructed and arranged as and for the purpose set forth.

HENRY YOUNT.
